UNITED STATES PATENT OFFICE.

RUDOLF A. HAGEN, OF MASON CITY, IOWA.

MACHINE GUN.

Application filed January 24, 1927. Serial No. 163,135.

The invention relates to machine guns. The object of the invention is to construct and provide a machine gun which will shoot without use of powder or the like. A further object of the invention is to provide a machine gun, the bullets whereof will not be inserted in cartridges containing powder or other explosives. A still further object of the invention is to provide a machine gun 10 the use whereof will be connected with comparatively little noise of explosion.

Other objects not specifically mentioned will be easily ascertained and understood from the following specification in connection with the drawings forming a part thereof.

In the drawings showing a preferred embodiment of the invention Figure 1 is a side view of a machine gun according to the invention. Figure 2 is a central vertical longitudinal section through said machine gun. Figure 3 is a section on line 3-3 of Figure 2. Figure 4 is a section on line 4-4 of Figure 2, and Figure 5 is a section on line 5-5 of Figure 2. A gun barrel 6 is screwed into the wall of an explosion chamber 7 of an internal combustion engine the body 8 of said combustion engine to which the combustion chamber is fastened contains a cylinder 9 and an intake channel 10. The carburetor 11 is fastened on the end of the intake 10 and communicates with a gas tank 12 fastened to and carried by the engine. Onto the free end of the cylinder 10 a housing 13 is fastened and in said housing a crank shaft 14 is journaled. Connecting rod 15 connects the crank of said shaft with the piston 16 adapted to reciprocate in the cylinder 9. A valve 17 of the well known 40 tappet type in the intake channel 10 prevents the gas from entering into the combustion chamber 7 as when said valve is in closed position in the usual way. A gear 19 is mounted on a prolongation 20 of the 45 crank shaft 14 and said gear meshes with a second gear 21 mounted upon a stud 22 fastened into the wall of the casing 13. A third gear 23 is mounted upon a shaft 24 journaled in the walls of the casing 13 and 50 extending through said casing. A cam 25 is mounted upon the shaft 24 and is adapted to engage the upper end of a tappet rod 26 adapted to engage the end of the valve stem 27 of the intake valve 17. The tappet rod 55 26 is slidably mounted in a sleeve 28 form-

ing an integral part of the body casting of the engine and extends into the interior of the casing 13 into the vicinity of cam 25. On the same side of the casing on which the gears 19, 21 and 23 are arranged, another 60 gear 29 is mounted upon a shaft 30 also extending through the casing 13 and journaled in the walls thereof. The shaft 30 is located underneath the shaft 24 and extends parallel thereto. The gear 29 meshes also 65 with the gear 21. The cam 31 is mounted upon the shaft 30 and arranged inside the casing 13.

A magazine 32 of the well known worm type adapted to contain bullets is detachably fastened to the lower part of the combustion chamber 7 adjacent the end of the barrel 6 screwed in the wall of the combustion chamber. As indicated in Figure 2 the 70 bullets 33 have the usual form of rifle bullets, but are not inserted into cartridges. These bullets will be fed by means of a spring 34 contained in the magazine in the usual way to the intake opening in the barrel. In order to regulate the feed of the 75 bullets and in order to insert the bullet in position in front of the barrel into said barrel a push rod 35 is slidably supported by a lug 36 on the cylinder wall. A spring 37 surrounds said push rod 35 and abuts 80 with one of its ends the lug and with its other end a stop 38 adjustably mounted on said push rod. A tappet rod 39 is slidably mounted in a lug 40 of the body of the engine and is adapted to engage the end of 85 the push rod 35. The other end of said tappet rod extends into the casing 13 into the vicinity of the cam 31 and is adapted to be actuated by said cam.

On the other end of the push rod 35 a pin 90 41 is fastened carrying a plate 42 which is arranged in such a manner that it is located directly in front of the bore of the barrel 6. A slot 43 is provided in the casing of the combustion chamber 7, and the pin 41 extends through said slot and the plate 42 covers said slot. When the cam 31 permits the rod 39 to slide into the casing 13, the spring 37 moves the rod 35 to the right in Figure 2. Thereby the pin 41 and the plate 95 42 is also moved towards the right. A channel 44, provided in the casting of the combustion chamber and forming, according to Figure 2, a prolongation of the channel in the magazine 32, will be uncovered so that a 100 105 110

bullet will be brought into position in front of the bore of the barrel 6. The movement of the cam 31 is timed in such a manner, that as soon as a bullet is brought into this position, the cam will force the tappet rod 39 and thereby the push rod 35 to the left in Figure 2 whereby the plate 42 will force the bullet located in front of the barrel into the bore thereof and will at the same time prevent the other bullets from being forced into the explosion chamber.

A sparkplug 45 is inserted in the wall of the combustion chamber 7 in the vicinity of the outlet of the antic channel 10. An electric conductor 46 connects said sparkplug with a timer 47 which, as indicated in Figure 3, is actuated by the shaft 30 rotated by means of the gear 29.

On the prolongation 20 of the crank shaft 20 outside of the gear 19 a fly wheel 48 is mounted and a handle 49 may be fastened to said fly wheel.

When the fly wheel is rotated the piston 15 will be reciprocated in the cylinder 9, and 25 at the same time the cam 25 will be rotated since the gear 14 will rotate with the fly wheel 48 and will actuate the gear 23 by means of the gear 21. Seeing that the gear 29 is also meshing with the gear 21, the push 30 rod 35 will be also actuated by rotating the fly wheel 48 and the timer 47 will time the explosions.

In order to prevent an accidental firing a lock 49 is provided which secures the push rod 35 from accidental movement. A lever 50 is pivotally mounted on the lug 36 at 51, and a spring 52 forces the upper portion of the lever 50 in a notch 53 provided in the push rod 35. As long as the upper portion of the lever 50 is in engagement with said notch, it is impossible for a bullet to be brought into position before the bore of the barrel 6. By pressing on the lower portion of the lever 50 the rod 35 becomes free for movement and when the fly wheel is rotated either by hand or by the movement of the piston in the cylinder, the cam 31 will actuate the push rod so that a bullet may be fitted into the barrel. The explosion of the 50 gases in the combustion chamber 7 will take the place of the exploding powder in a cartridge and will drive the bullets through the barrel.

From the above it will be understood that 55 the engine may be run without any bullets being fired. When the push rod 35 is se-

cured by means of the lock lever in the position shown in Figure 2, the cam 31 may rotate without actuating said rod and the spring 37 is prevented from moving said rod 60 toward the cam. In this manner it is possible to fire a single shot by pressing on the lower part of the lever 50 and then release said lever 50 against the rod 35 and as soon as the notch 53 will come in registration 65 with the notch in the lever, said lever will engage said notch and lock the push rod 35 and secure it against movement. The whole machine gun can be mounted upon a stand 54 as indicated in Figures 1 and 2. In order 70 to facilitate the training of the gun ball-bearing 55 may be provided on said stand. The elevation of the gun is also provided for as indicated by the slotted arc. To facilitate these operations a handle 57 is 75 attached to the casing 13. From the timer 47 an electric connection 58 leads to a battery not shown and a second connection 59 leads from the battery to the body of the casing 13 to close the circuit.

What I claim as new and desire by Letters of Patents is:

1. In a machine gun of the class described an internal combustion engine, a gas tank therefor a carburetor connected to said gas tank and communicating with said engine, an intake valve governing the said communication between the carburetor and the engine, a gun barrel communicating with the explosion chamber of the said engine and 90 adapted to contain bullets, means for feeding said bullets one by one into said barrel, means for controlling the movement of the intake valve, means for controlling the movement of the bullet feeding means, and means 95 common to the two movement controlling means for actuating said two means.

2. In a machine gun of the class described an internal combustion engine, an intake valve therefor, a gun barrel communicating 100 with the explosion chamber of said engine, a magazine adapted to contain bullets, means for removably fastening the magazine to the engine, a bullet feeding device adapted to feed bullets one by one into the 105 barrel, a cam controlling the movement of said intake valve, a second cam controlling the movement of the bullet feeding device, and means common to the two cams for controlling the movement of said two cams.

In witness whereof I affix my signature.

RUDOLF A. HAGEN.
